7 Claims. (Cl. 202—42)

1

This invention relates to a process for separating xylenes from mixtures such as petrol or cracked petrol fractions which contain them together with non-aromatic compounds of the paraffin, naphthene and olefine type.

By "xylenes" in this specification we mean, in addition to ortho-, meta-, and para-xylene, also ethyl benzene and styrene.

It is already known to separate xylenes from associated non-aromatics by azeotropic distillation with 2-methoxy-ethanol in the presence or absence of water. In the case of the use of 2-methoxy-ethanol in conjunction with water it has been proposed to effect the removal and recovery of the 2-methoxy ethanol for re-use by employing such a quantity of water that the overhead fraction consists substantially of ternary azeotropes between the non-aromatic compounds, 2-methoxy-ethanol and water, or such a quantity of water that separate zones, one containing 2-methoxy ethanol and non-aromatics, the other containing water and non-aromatics, are maintained in the distillation column.

According to our invention we separate xylenes of the kind hereinbefore defined from non-aromatic compounds of the paraffin and/or naphthene and/or olefine type present in hydrocarbon feedstock such as petrol or cracked petrol fractions by continuous azeotropic distillation of the feedstock with 2-methoxy ethanol containing a quantity of water insufficient both to allow two liquid phases to form in the distillation column itself and to form ternary azeotropes with all the non-aromatic compounds in the overhead fraction, but sufficient to cause separation of the overhead fraction from said azeotropic distillation into two liquid phases on cooling to such a temperature that the lower one of these two liquid phases contains most of the 2-methoxy-ethanol together with most of the water, the upper phase being rich in non-aromatic compounds, the xylenes being taken off in the bottom fraction from the main azeotropic distillation.

The lower phase is, according to a feature of the invention, preferably continuously recycled without any further treatment, by returning it to an intermediate point of the main column at or near the point at which the fresh hydrocarbon feed is introduced, no attempt being made to maintain separate 2-methoxy-ethanol and water zones in the column.

The upper one of the two liquid layers referred to may be refluxed to recover the 2-methoxy-ethanol which it contains and which, together with some of the non-aromatic compounds, passes overhead, and may be recycled to the vessel in which the two layers form. The liquid from the bottom of this refluxing

column consists of substantially pure non-aromatic hydrocarbons.

In practice it has also been found desirable to operate the main azeotropic column in such a manner that the bottom fraction contains a few per cent of 2-methoxy-ethanol and to recover this material in a separate fractionating column, returning the overhead fraction from this column, which consists of the 2-methoxy-ethanol together with some xylenes, to an intermediate point of the main azeotropic column at or near the point at which fresh hydrocarbon feed and recycle material are introduced. The liquid from the bottom of this refluxing column is then xylene substantially free from 2-methoxy-ethanol.

The feedstock should preferably have a boiling range of 125—150° C., more preferably 130—145° C.

The process is preferably carried out at substantially atmospheric pressure although if desired it may be carried out at either moderately reduced or moderately elevated pressures.

The quantity of water to be used in the process of our invention is limited on the one hand by the amount which causes phase separation in the main azeotropic column and on the other hand by the amount necessary to produce satisfactory phase separation of the condensed overheads in the decanter. In practice it has been found that our process may be conducted with the 2-methoxy-ethanol fed to the main azeotropic column containing approximately 1 to 9 per cent water. Preferably the 2-methoxy-ethanol fed to the main azeotropic column should contain about 3.5 per cent water.

The single figure of the accompanying drawing illustrates diagrammatically and by way of example, only, a system in which the present invention may be carried into effect.

In this figure, 1 is the main azeotropic distillation column with boiler heater 2 and internal condenser 3. The feedstock enters at 4 halfway up the column. The overhead fraction is taken to condenser 5 cooled by cooling means 6 and thence through a further cooler 7 into a decanter 8 where it separates into two layers. The lower layer is recycled to the entry point 4 of the feedstock into column 1. The upper layer is stripped of 2-methoxy-ethanol in column 9 heated by heating means 10 and provided with internal condenser 11; the non-aromatics leave the bottom of column 9 substantially free of 2-methoxy-ethanol. The overhead fraction from column 9, being an azeotropic mixture of 2-methoxy-ethanol and non-aromatics, is recycled to the decanter 8. The bottom fraction of column 1 is rich in the desired aromatics. It is taken to a separate column 12 heated at 13 and with internal condenser 14 where azeotropic mixtures of aromatics and 2-methoxy-ethanol distil

3

off and are taken back to the entry 4 to column 1. The bottom fraction of column 12 consists of the desired aromatic compounds in substantially pure condition.

Example I

A mixture containing 70.6% by volume of cracked petrol boiling within the range 130-145° C., 28.5% by volume of 2-methoxy-ethanol and 0.9% by volume of water was fed to the mid point of a laboratory continuous fractionating column 1 operating at atmospheric pressure. The column 1 had an internal diameter of 1½" and a packed length of 6 ft. of ½" porcelain Raschig rings. The fractionation was conducted at a 15 reflux ratio of approximately 5/1 and a vapour velocity of about 0.9 ft./second.

The cracked petrol cut contained 54.9% by volume of aromatics (ortho-, meta-, para-xylene and ethyl benzene) and 45.1% by volume of non-aromatics (paraffins, naphthenes and olefines). The olefine content of the cut was 4.2% by volume and it contained approximately 0.5% dienes and 0.1% styrene.

61.3% by volume of the feed was taken overhead 25 at about 115° C. and 38.7% by volume was removed as bottoms fraction at about 138° C.

The overhead fraction contained substantially all of the water present in the feed and 95% by volume of the 2-methoxy-ethanol. 80% by volume of the hydrocarbons in the overhead fraction were non-aromatics. The liquid at the bottom contained no water and a few per cent only of 2-methoxy-ethanol. Of the hydrocarbons in the bottom fraction 91% by volume were aromatics.

The overhead fraction condensed in condenser 5, on cooling to 68° C. in cooler 7, became heterogeneous, and at 35° C. there was, in decanter 8, an upper phase forming 46% by volume of the whole. The upper phase contained 77% by volume of the hydrocarbons contained in the overhead fraction together with some 2-methoxy-ethanol. The lower phase contained substantially all of the water contained in the overhead fraction, the bulk of the 2-methoxy-ethanol and some hydrocarbons. At lower temperatures the separation between the hydrocarbons and 2-methoxy-ethanol was more nearly complete.

Example II

A mixture containing 49.4% by weight of hydrocarbons, 1.0% by weight of water and 49.6% by weight of 2-methoxy-ethanol was fed continuously at a rate of 7.07 kg./hr. to the mid-point 4 of a continuous distillation column 1 which was 4" in diameter and contained a packing of 20 feet of ¼" x ¼" unglazed porcelain rings. The feed mixture was homogeneous above 30.8° C., below which it separated into two liquid phases. The hydrocarbon portion consisted predominantly of material boiling in the range 125-150° C. but contained in addition 12% by weight of material boiling below 125° C. and 15% by weight of material boiling above 150° C. It consisted of 1.7% by weight of unsaturated hydrocarbons, 52.8% by weight of naphthenes and paraffins and 45.5% by weight of aromatics. Column 1 was operated at atmospheric pressure with a reflux ratio of 2.95, an overhead product rate of 5.56 kg./hr. and a base product rate of 1.51 kg./hr. The overhead product contained substantially all of the water entering in the feed and separated, after condensation in 5 and cooling in 7, into 42% by weight of predominantly hydrocarbon upper layer 70

4

and 58% by weight of predominantly 2-methoxy-ethanol lower layer. This overhead product contained 48.9% by weight of hydrocarbons consisting of 32.0% by weight of aromatics, 1.8% by weight of unsaturated compounds and 66.2% by weight of naphthenes and paraffins. The bottom fraction of column 1 contained 49.0% by weight of 2-methoxy-ethanol and 51.0% by weight of hydrocarbons, consisting of 94.1% by weight of aromatics, 5.1% by weight of naphthenes and paraffins and 0.8% by weight of unsaturated compounds.

The separation was more difficult than in Example I as a result of the wider boiling range of the hydrocarbon feedstock.

I claim:

1. A process for separating at least one member of the group consisting of xylenes, ethyl benzene and styrene from non-aromatic compounds which comprises continuously azeotropically distilling in a column the mixture from which said member is to be separated, with the addition of 2-methoxy-ethanol and of an amount of water which is insufficient both to allow two liquid phases to form in said column and to form ternary azeotropes with all the non-aromatic compounds which distill off in the overhead fraction in said column but which is sufficient to cause separation of said overhead fraction into two liquid phases on cooling to a temperature which causes the lower one of said two liquid phases to contain most of the 2-methoxy-ethanol together with most of the water and the upper one of said liquid phases to be rich in non-aromatic compounds, said addition of 2-methoxy-ethanol containing from 1 to 9% of its own weight of water, the volume ratio of 2-methoxy-ethanol to non-aromatic hydrocarbons in the mixture from which said member is to be separated being from about .9 to about 1.35:1, cooling said overhead fraction to cause it to separate into the aforesaid two liquid phases taking off the members of said group in the bottom fraction from said column and continuously recycling, without any further treatment, said lower phase to said column to act as said addition of 2-methoxy-ethanol and water.

2. A process as claimed in claim 1 which also comprises re-fractionating said upper phase for recovery of 2-methoxy-ethanol.

3. A process as claimed in claim 1 which also comprises fractionating the bottom fraction of said column in a further column.

4. A process as claimed in claim 1 which also comprises fractionating the bottom fraction of said column in a further column and recycling the overhead fraction from said further column to the first said column.

5. A process as claimed in claim 1 which comprises feeding said column with a hydrocarbon mixture having a boiling range of 125-150° C.

6. A process as claimed in claim 1 which comprises feeding said column with a hydrocarbon mixture having a boiling range of 130-145° C.

7. A process as claimed in claim 1 in which the 65 2-methoxy-ethanol used contains approximately 3.5 per cent of its own weight of water.

GORDON HOWARD FOXON.
